UNITED STATES PATENT OFFICE.

JENNIE SHEILS, OF NEW YORK, N. Y., ASSIGNOR TO THE BUTTERICK PUBLISHING COMPANY, (LIMITED,) OF SAME PLACE.

DESIGN FOR A LADY'S WALKING-SKIRT.

SPECIFICATION forming part of Design No. 17,882, dated November 15, 1887.

Application filed October 15, 1887. Serial No. 252,489. Term of patent 3½ years.

To all whom it may concern:

Be it known that I, JENNIE SHEILS, of the city, county, and State of New York, have invented and produced a new and original Design for a Pattern of a Lady's Walking-Skirt; and I do hereby declare that the engraved prints accompanying this specification convey to any one accustomed to using paper patterns a clear understanding of how a garment made up by the pattern will appear.

The design shows a round walking-skirt that exhibits a plaited panel drapery at the left side falling to the edge, a front drapery that falls in a loose puff at the bottom of the skirt and displays loose loops at its front edge and drap-

ing plaits in its upper and back edges, and a full back drapery that falls even with the edge of the skirt all the way across and displays bournous loops and gathers at the belt and irregular folds all the way down.

What I claim as my invention, and desire to secure by Letters Patent, is—

The design for a lady's walking-skirt, as shown in the engraved prints accompanying this specification.

JENNIE SHEILS.
